ROBERT HOPE-JONES, OF NORTH TONAWANDA, NEW YORK, ASSIGNEE TO THE RUDOLPH WURLITZER MANUFACTURING COMPANY, OF NORTH TONAWANDA, NEW YORK, A CORPORATION OF NEW YORK.

COMBINATION STOP MECHANISM FOR ORGANS.

1,119,602.

Specification of Letters Patent.

Patented Dec. 1, 1914.

Application filed December 27, 1910. Serial No. 599,434.

To all whom it may concern:

Be it known that I, ROBERT HOPE-JONES, of North Tonawanda, in the county of Niagara and State of New York, have invented certain new and useful Improvements in Combination Stop Mechanism for Organs; and I do hereby declare the following to be a full, clear, and exact description of the same, reference being had to the accompanying drawings, forming a part of this specification, and to the reference-numerals marked thereon.

The present invention relates to musical instruments and more particularly to organs or instruments constructed on the general scheme of an organ, and it has for an object to provide a simple and efficient switch mechanism through the medium of which certain parts of the organ may be thrown into or out of operation.

A further object of the invention is to provide an electrical switch of this nature for electro-pneumatically operated organs having on and off positions, in one or both of which it is retained mechanically against movement to the other.

The improvements are further directed toward improving the stop mechanism of the organ by simplifying and making more convenient and certain in operation the switching devices whereby the different stop keys of a manual are selected on the different combination keys or pistons, as they are called.

To these and other ends the invention consists in certain improvements and combinations of parts all as will be hereinafter more fully described, the novel features being pointed out in the claims at the end of the specification.

In the drawings: Figure 1 is a top plan view of a switch mechanism constructed in accordance with and illustrating one embodiment of my invention; Fig. 2 is a vertical section therethrough taken substantially on the line 2—2 of Fig. 1 and showing in similar section the wind-supply-mechanism for the motors; Fig. 3 is a section taken substantially on the line 3—3 of Fig. 50 1 showing one of the valve members for controlling the motors and its operating means; Fig. 4 is a diagrammatic view showing that portion of the stop mechanism of

an organ combining the switch-mechanism which is concerned with the automatic drawing of certain stop-keys upon the pressing of a piston for playing purposes; Fig. 5 is also a diagrammatic view illustrating other portions of the stop mechanism such as are concerned with the initial setting of the certain stop keys on a given combination piston, and Fig. 6 is a diagrammatic assembled view of the mechanisms shown in Figs. 4 and 5 but with the plural elements illustrated as such.

Similar reference numerals throughout the several figures indicate the same parts.

The switch mechanism of the present embodiment of the invention is adapted to electro-pneumatically operated organs and referring first more particularly to Figs. 1, 2 and 3, 1 indicates a suitable support preferably horizontally disposed and carrying a plurality of switches, a description of one of which will suffice for all. A channel or conduit 2, extending through the support, forms a wind chest from which leads upwardly a branch passage 3 opening on the upper face of the support. Over this opening is placed a bellows 4 communicating with the passage at 5 to be fed thereby and comprising upper and lower leaves 6 and 7 which, in the present instance, are not hinged together, but merely connected by the flexible portion.

A supporting member 8 of insulating material extending across the member 1 carries three laterally projecting electrical contact pins 9, 10 and 11, the first two of which are in substantial vertical alignment while the third one is to one side thereof. A pair of yielding switch arms 12 and 13, preferably formed of a single piece of resilient wire, or otherwise electrically connected, are carried by and extend upwardly from the upper leaf 6 of the bellows or motor 4. One of these arms, the arm 13 in the present instance, travels in constant engagement with the contact pin 11, while the other, acting in opposition to it, is provided with a shoulder 14, preferably formed by bending a partial loop in the wire, which shoulder engages one or the other of the contacts 9 and 10 according to whether the bellows is extended or collapsed. In the extended position, the shoulder has a locking engage-

ment above the contact pin 9 whereby it maintains itself in such contact and supports the upper leaf 6 of the bellows so that the latter is held extended whereas upon the contraction of the bellows as by opening the passage 3 to a vacuum, the switch arm 12 yields laterally disengaging the shoulder from the contact pin 9 and locking it beneath or in engagement with the lower contact pin 10, as shown at the left in Fig. 4. A very cheap and simple pneumatically operated switch is thus provided.

Organs of a type to which my present improvements are adapted are provided, usually in a row just beneath the keys of each manual, with a plurality of keys or "combination pistons", as they are called, the object of which is to draw, by pressing any one of them, a certain combination, coupled to that particular one, of the stops on the manual simultaneously and without the necessity of drawing each stop individually. Certain combinations are used under certain circumstances and it is necessary to change the stop keys to be drawn by a given combination piston from time to time. This is done by first drawing the individual stop keys wanted in the combination, then pressing the combination piston to which they are to be coupled and simultaneously pressing what is termed a "locking" or "general piston" located at a convenient point, there being one on the console for each manual and each row of combination pistons. The stop keys are then returned and the locking piston released whereupon every time that particular combination piston is pressed independently of or without simultaneously depressing the general or locking piston, the same combination of stop keys is drawn with the one movement.

The present invention is shown diagrammatically embodied in a mechanism by means of which these results are obtained and referring to Fig. 4, more particularly, 15 indicates a stop key pivoted at 16 and provided with bellows 17 and 18, the expansion of the former of which draws the stop, while similar action in the other returns it. The first is under the control of an electro-magnet 19 and the second under the control of a similar magnet 20, the windings of which are connected, respectively, by wires 21 and 22 to the contact pins 10 and 9 of the switch previously described. These circuits are both energized by the generator 23 and are both controlled by a combination piston 24, the function of which, in the present instance, is merely that of a switch, as shown. Therefore, when the combination piston is pressed or drawn it closes a circuit from generator 23 through wire 25, piston 24, wire 26, electro-magnet 27 and wire 28, back to the generator. The electro-magnet 27 controls a pneumatic 29 having a contact plate

30 that closes contacts 31. Another circuit is thereby established from the generator through a wire 32 (considering the switch 12-13 to be in the position shown in Fig. 4), wire 33, magnet 20, wire 22, contact 9, 70 switch arm 12, switch arm 13, contact 11, wire 34, contacts 31 and back to the generator through wire 35. This will cause the bellows 18 of the stop key to operate and the latter to return from its drawn position. If, however, the switch arm 12 is held by its motor 4 in lowered position, the circuit will pass through the other magnet 19 and the lower contact pin 10 and cause the upper bellows 17 of the stop key to operate, drawing the latter.

The switches comprising the bellows or motors 4 are arranged in longitudinal and transverse rows, the former being indicated in Fig. 1 by the letters A—A, A¹—A¹, A²—A², and the latter by the letters B—B, B¹—B¹, B²—B². There is a row A—A, A¹—A¹, A²—A², for each combination piston and one in each row for each stop key on the manual, the switches in rows A—A controlling the same stop-key being arranged opposite each other so that the transverse rows B—B, B¹—B¹, B²—B², all relate to the same stop key and there is a possible circuit, as above described, through each switch in that row to that stop key, each circuit under the control of a different combination piston 24. The passages 3 of the motors 4 in each transverse row B—B, B¹—B¹, B²—B² are all fed from a single wind chest 2, there being as 100 many of these chests as there are rows B—B, B¹—B¹, B²—B². The passages 3 of each row A—A, A¹—A¹, A²—A², are, however, simultaneously opened or closed by a valve member having, in the present instance, the 105 form of a slider 36 provided with an aperture 37 for each passage in that row.

Referring now to Fig. 5, the combination piston 24, when pressed, closes, at one point, an independent circuit to an electro-magnet 110 38 controlling a bellows 39 in a wind chest 40, which bellows or motor is connected at 41 with a slider 36 and the operation of the bellows draws the slider and operates all the motors 4 of the switches in one of the rows 115 A—A. This circuit, however, passes through the beforementioned locking or general piston 42 which is also in the nature of a switch, the circuit being generator 23, wire 43, locking piston 42, wire 44, combination 120 piston 24, wire 45, magnet 38, wire 46 and back to the generator. One locking piston 42 is sufficient. The locking piston 42 alone closes another circuit from generator 23, locking piston 42, wire 47 through electro-magnets 48 and 49 and wire 50 back to the generator. These magnets 48 and 49, respectively, control the passage of wind from suitable sources of supply 51 and 52 into wind chests 53 and 54, the former at a posi- 125

tive pressure and the latter at a negative pressure or vacuum, both of which wind-chests supply one of the chests 2 at different times through a common passage 55. The supply to the chest 2, whether positive or negative, is selected through the action of an electro-magnet 56 that operates a valve 57 which in turn causes the actuation of a valve 58 that allows the vacuum chamber 54 to communicate with the passage 55 through a port 59, or the wind chamber 53 through a port 60. The circuit through the magnet 56 is closed when the stop key 15, being drawn, closes contact 61, the circuit being from generator 23 through wire 62, magnet 56, wire 63, contact 61, wire 64 and wire 50 back to the generator.

As to the general operation, it must be borne in mind that each stop key 15 controls one duplex wind supply mechanism, such as shown in Fig. 5, embodying the magnet 56 and that feeds one chest 2; that the switch of each row $A-A$, A^1-A^1 , A^2-A^2 each of which switches has its separate circuit; all lead however to the same stop key operating magnets 19 or 20; that one of these circuits in any one row $A-A$, A^1-A^1 , A^2-A^2 , is closed at another point (31) only when a combination piston 24 is pressed, namely, that one lying in the row $A-A$, A^1-A^1 , A^2-A^2 , the slider 36 of which is controlled by the same combination piston, as shown in Fig. 5, (there being a motor 29 for each combination piston), and that none of the combination pistons can operate its slider 36 unless the locking piston 42 common to all the combination pistons is simultaneously operated.

Fig. 5 is illustrative of the manner in which the stop keys are originally set or coupled onto the different combination pistons, while Fig. 4 is illustrative of the manner in which the latter control the stop keys when they, namely the combination pistons, are subsequently operated. Assuming in Fig. 5 that the stop key 15 is to be coupled onto the combination piston 24, that key is first depressed which, through the contacts 61, operates the magnet 56 and through the latter the valve 57 so that it is ready to open the chest 2 of any one transverse row of switches $A-A$, A^1-A^1 , A^2-A^2 , individual to the key 15 to the vacuum in chest 54, which chest has not, however, been supplied by the source 52 and, therefore, the net effect of drawing the stop key is simply to set this valve. Then the combination piston 24 is operated and also the locking piston 42, which latter permits the former to draw its slider 36 and open the passages 3 to the switch operating motors 4 arranged in the particular row $A-A$, A^1-A^1 , A^2-A^2 , that slide controls. But the locking piston 42 also opens the source of vacuum or negative pressure supply 52 into the chest 54 so

that the switch arm 12 or that one in the row $A-A$ or A^1-A^1 or A^2-A^2 , the passages 3 of which are open, that receives pressure from the particular transverse channel 2 that has been filled by the stop key 15 will be operated to the lower or "on" contact pin 10 unless it happens to be already there. When the combination piston is released, its slider closes that particular switch motor from air pressure and one of the circuits (21 etc., Fig. 4) to the mechanical setting devices of the stop key 15, which it is to later control, is set closed at that point. With the release of the locking piston, the wind supply is shut off and the combination piston is thereafter prevented from actuating its slider when pressed until the locking piston is pressed again, simultaneously therewith. Therefore, returning to Fig. 4, during the playing of the organ when the combination piston 24 is pressed the only result is that a circuit is closed through magnet 19 at 31, it being one of the various circuits to that magnet, and the stop key 15 is drawn automatically.

While a passage 3 to a motor 4 controlling the switch in one of the circuits to each individual stop operating means or stop key of a set is opened every time any slider 36 is drawn through the pressing of a combination piston in conjunction with a locking piston, only those motors are operated which are fed from the particular chest 2 that is supplied from the supply mechanism that is placed in operation through magnet 56 by the drawing of that particular stop key in arranging the combination in the first instance.

In case, during the setting of the combination, the stop key 15 is not desired on a particular piston it is not drawn, hence the magnet 56 is not operated, the chest 2 is supplied with wind instead of vacuum when the locking piston is pressed and the switch arm 12 is moved by the inflation of the motor 4 to the "off" position or in engagement with the contact 9 which leads the circuit established by the combination piston in Fig. 4 so that current will pass through the magnet 20 instead of the magnet 19 and return the stop key to drawn position, if it is not already there.

As before stated, applicant has, for the sake of clearness, illustrated in Fig. 4 the arrangements whereby a particular combination piston 24 of a set draws a particular stop 15 of a set after that stop has been arranged in the combination with that particular combination piston, whereas Fig. 5 illustrates only the arrangements whereby that particular stop is prearranged on the combination with that particular combination piston 24. The two systems being independent in as far as they operate at different times, this mode of illustration is be-

lieved to make more intelligible the function of each, but in Fig. 6 both sets are shown joined together, a plurality of stop keys being shown as well as a plurality of combination pistons. In this view, which is for the most part diagrammatic, the additional stop key and the additional combination piston, as well as circuits and parts controlling or under the control of each, are indicated by the same reference numerals as the parts of which they are duplicates, but are distinguished by prime marks in connection with the reference numerals. The view also illustrates that the several switches in each transverse row B—B, B¹—B¹, B²—B² are arranged in parallel on the circuit of the operating mechanism of one stop key, while all the switches in each longitudinal row A—A, A¹—A¹, A²—A² are all in parallel on a circuit elsewhere controlled by one particular combination piston. There may be as many combination pistons as are desired in view of the number of possible combinations that it is wished to provide for, although there need be only one locking piston 42 for all the combination pistons 24, 24¹, as shown.

I claim as my invention:

1. In a pneumatic organ, the combination with a plurality of different stop keys and separate means for operating the same, each under the control of any one of a plurality of devices, of means for rendering each of said devices operative or inoperative, a bellows for actuating each of the said last mentioned means, there being a set of bellows for the said means of each stop key, a plurality of means each under the control of a stop key for supplying wind to the set of actuating bellows of that key, a plurality of valve members each controlling a series of bellows comprising one from each stop key set, a combination piston for each valve member adapted to also control the stop key operating devices and a locking piston controlling the connections between the combination pistons and valve members and also the wind supply.

2. In an electro-pneumatic organ, the combination with a plurality of different stop keys, a plurality of circuits and separate means each under the control of any one of such plurality of circuits for operating the keys of a switch for each circuit, a bellows for actuating each switch, there being a set of bellows for the switches of each stop key, means each under the control of a stop key for supplying wind to the set of switch actuating bellows of that key, a plurality of valve members each controlling a series of bellows, comprising one from each stop key set, a combination piston for each valve member adapted to also close the stop key operating circuits at one point, and a locking piston constituting a connection between the

combination pistons and valve members and also constituting a means for controlling the wind supply.

3. In an electro-pneumatic organ, the combination with a plurality of different stop keys, a plurality of circuits and separate means each under the control of any one of such plurality of circuits for operating the keys, of a switch for each circuit, a support, a plurality of bellows, therein for actuating the respective switches arranged in longitudinal and transverse rows, each transverse row comprising a set for the switches of a single stop key, a separate wind chest in the support extending beneath and having branch passages connected to the units of each transverse row or set of bellows, means under the control of the stop key of that set for supplying wind to each chest, a plurality of sliders extending beneath the longitudinal rows of bellows, each controlling a series of passages, said series comprising a passage to a bellows in each stop key set, a combination piston for each slider adapted to also close the stop-key-operating circuits at one point and a locking piston constituting a connection between the combination piston and sliders and also constituting a means for controlling the supply to the wind chest.

4. In a selecting mechanism for organs, the combination with a support, and a plurality of pneumatics arranged thereon in longitudinal and transverse rows, of a plurality of independent conduits in the support each forming a wind chest provided with passages leading to the respective pneumatics of a transverse row, a slide valve member for simultaneously controlling the passages to the pneumatics of each longitudinal row and means for selectively supplying wind to the wind chests.

5. In a selecting mechanism for organs, the combination with a plurality of stop keys, operating means for each embodying and under the control of any one of a plurality of circuits and a switch in each circuit, of a plurality of series of pneumatics each pneumatic in each series being arranged to actuate one of the switches in one of the circuits of the same stop key, a plurality of independent wind chests each common to and adapted to supply one series of pneumatics, a valve member for simultaneously controlling a passage to one pneumatic of each series and means for selectively supplying wind to the wind chests.

6. In a selecting mechanism for organs, the combination with a plurality of stop keys, operating means for each embodying and under the control of any one of a plurality of circuits and a switch in each circuit, of a plurality of series of pneumatics each pneumatic in each series being arranged to actuate one of the switches in one of the circuits of the same stop key, a plural-

ity of independent wind chests each common to and adapted to supply one series of pneumatics, a valve member for simultaneously controlling a passage to one pneumatic of each series, a combination piston controlling each valve member and also the circuits of the switches for the pneumatics which that valve member controls, a means under the control of each stop key for supplying the wind chest that feeds the pneumatics for the

switches in the circuits of that key and a second controlling device for said means also arranged to control the connection between each combination piston and its valve member.
